UNITED STATES PATENT OFFICE.

JOSEPH VAN ACKEREN, OF PITTSBURGH, PENNSYLVANIA, ASSIGNOR TO THE KOPERS COMPANY, OF PITTSBURGH, PENNSYLVANIA, A CORPORATION OF PENNSYLVANIA.

STANDPIPE APPARATUS.

Application filed December 13, 1923. Serial No. 680,532.

To all whom it may concern:

Be it known that I, JOSEPH VAN ACKEREN, a citizen of the United States, residing in Pittsburgh, in the county of Allegheny and 5 State of Pennsylvania, have invented a new and useful Improvement in Standpipe Apparatus, of which the following is a specification.

The object of this invention is to provide 10 an improved standpipe construction for the discharge of the distillation products from carbonizing plants, such as by-product coke oven plants of the Koppers cross-regenerative type exemplified in the prior Letters 15 Patent of the United States of Joseph Becker, for coking retort oven, No. 1,374,546, granted April 12, 1921. According to the invention, provision is made for directly spraying the seating portion of the body of 20 the valve between the standpipe and the collecting main, and also the gases before they reach the collecting main, without any danger whatever of the spray entering the coking chamber or retort. Provision is also 25 made for the spray to descend vertically on an upwardly presented and preferably cupped valve body, around which it flows off to or into the collecting main, and this manner of spraying the valve body is particu- 30 larly facilitated by locating the valve at the bottom of a discharge pipe that descends from and in proximity to the riser pipe. There is furthermore provided an improved 35 form of connection between the standpipe apparatus and the collecting main, whereby the spray liquor is compelled to flow into the bottom of the collecting main, from 40 which the liquor may be discharged and disposed of in a subsequent treatment for the recovery of ammonia and tar.

In addition to the general objects recited above, the invention has for further objects such other improvements or advantages in construction and operation as may be found 45 to obtain in the structures and devices hereinafter described or claimed.

In the accompanying drawings forming a 50 part of this specification and showing for purposes of exemplification a preferred form and manner in which the invention may be embodied and practiced, but without limit-

ing the claimed invention specifically to such illustrative instance or instances:

Figure 1 is an elevational view of a standpipe apparatus constructed in accordance 55 with the invention, the view showing the apparatus applied to the gas outlet of one of the coking chambers of a coking retort oven and connected with a collecting main in which the gases and distillation products of 60 a battery of coke ovens are collected and subsequently discharged to the by-product recovery apparatus.

Fig. 2 is a top plan view of the apparatus; 65

Fig. 3 is a vertical sectional view of the same.

The same characters of reference designate 70 the same parts in each of the several views of the drawings.

In the illustrated embodiment of the invention there is shown a fragment of a coking chamber 11 provided in the top 12 with a gas outlet 13 through which discharge 75 the gases from the distillation of the coal. The coking chamber 11 may be one of a battery of similar chambers, for example, as set forth in the prior patent of Joseph Becker No. 1,374,546, hereinbefore mentioned. The discharge outlet 13 of each 80 coking chamber 11 is equipped with a standpipe apparatus, and the standpipes of the several coking chambers are connected with and discharge into a common collecting main 14 which extends along one side of the battery. The collecting main 14 may be provided at one end with an elbow 15 for connecting said main to the gas pipe through 85 which the gases and other products pass to the by-product recovery apparatus.

In accordance with the invention, the standpipe apparatus includes a riser pipe 16 constituted, preferably, of a lower vertical pipe section 17 mounted directly over the gas outlet 13 and from which the gases and distillation products pass into an upper vertical pipe section 18 set in the top of the lower section 17. At the top of the upper section 18 there is provided an inspection hole 19 normally closed by the pivoted manually-operable cover 20.

From the top of the riser pipe 16 the

gases pass into the downwardly curved upper discharge pipe section 21 and from the bottom of said section 21 into the slightly downwardly inclined lower discharge pipe section 22. The lower discharge section 22 projects laterally from the upper section 18 of the riser pipe but has communication only with the bottom of the discharge section 21, in order to enforce passage of the gases first 10 upwardly to the top of the riser pipe and thence downwardly through the discharge pipe of the standpipe apparatus before the gases pass into the collecting main 14. The lower discharge pipe section 22 of each 15 standpipe apparatus is connected by a short pipe section 23 with the side of the collecting main, the connecting pipe 23 being preferably located near the bottom of the collecting main, as shown, and below the longitudinal axis of said main.

Referring more particularly to Fig. 3, the upper discharge pipe section 21 is provided with a tapered portion 24 which projects within the inclined discharge section 22 and provides a seat 25 for a drop valve 26. The valve body 26 may be of the dished plate type, with the concave surface uppermost, so that, when lifted to closed position, the tapered portion 24 enters and seats securely within the concave upper surface of the valve body though permitting an overflow of sealing and cleansing liquid around the periphery of said body, as hereinbefore set forth. The valve body 26 is mounted by ears 30 27 on a rock shaft 28 which projects through the discharge pipe section 22 and is provided at its outer end with an operating handle 29. The handle 29 is lifted to lower the valve into open position and lowered, as 35 shown by dot and dash lines in Fig. 1, to lift the valve into closed position for shutting off the standpipe from the collecting main. This is usually done at the time of 40 charging the corresponding coking chamber or pushing out the coke. When in the valve closing position the handle 29 may be hooked under a lug 30 projecting from the side of the riser pipe 16, in order to hold the valve body 26 up securely against the seat 45 24.

The above described construction provides an extremely simple and economical means for permitting the gases and the valve body itself to be sprayed, without any danger of 50 the spray liquor entering the riser pipe and falling into the coking chamber or retort. The spray liquor may be introduced into the gases as they pass downwardly through the discharge pipe sections 21 and 22 from a 55 nozzle 31 set into a port 32 located in the top of pipe section 21 and just over the valve body 26. When the valve 26 is open the spray from the nozzle 31 will thoroughly flush out the concave upper surface of the 60 valve body and will discharge through the 65

lateral connections 22 and 23 directly into the bottom of a collecting main 14.

My application Serial No. 90,693, filed February 25, 1926, I have directed to the specific combination feature of a discharge pipe and valve that are both continuously flushed, which is a combination feature that is of utility in other carbonization apparatus besides riser-pipe or standpipe apparatus.

The invention as hereinabove set forth 75 may be variously embodied within the scope of the claims hereinafter made.

I claim:

1. A standpipe apparatus for conveying 80 distillation gases from a carbonization chamber to a collecting main, comprising: a riser pipe receiving at its lower end the gases, an upper discharge pipe curving downwardly from the top of said riser pipe, a lower discharge pipe inclining laterally 85 from the riser pipe and connected laterally with the collecting main below the longitudinal axis of the latter, said upper discharge pipe projecting within said lower discharge pipe to form a valve seat, a drop 90 valve body located within the lower discharge pipe and movable upwardly against said seat to shut off the riser pipe from the collecting main, and a spray nozzle mounted in the top of the upper discharge pipe above 95 the valve body for spraying downwardly through the connected pair of discharge pipes and also on to the movable valve body.

2. A standpipe apparatus for conveying 100 distillation gases from a carbonization chamber to a collecting main, comprising: a riser pipe receiving at its lower end the gases, an upper discharge pipe extending from the top of said riser pipe, a lower discharge pipe inclining laterally from the 105 riser pipe and connected laterally with the collecting main below the longitudinal axis of the latter, said upper discharge pipe projecting within said lower discharge pipe to form a valve seat, a drop 110 valve body located within the lower discharge pipe and movable upwardly against said seat to shut off the riser pipe from the collecting main, and a spray nozzle mounted in the top of the upper discharge pipe above the valve 115 body for spraying downwardly through the connected pair of discharge pipes and also on to the movable valve body.

3. A standpipe apparatus for conveying 120 distillation gases from a carbonization chamber to a collecting main, comprising: a riser pipe receiving at its lower end the gases, an upper discharge pipe extending from the top of said riser pipe, a lower discharge pipe connected laterally with the collecting main 125 below the longitudinal axis of the latter, said upper discharge pipe projecting within said lower discharge pipe to form a valve seat, a drop valve body located within the lower discharge pipe and movable upwardly 130

against said seat to shut off the riser pipe from the collecting main, and a spray nozzle mounted in the top of the upper discharge pipe above the valve body for spraying downwardly through the connected pair of discharge pipes and also on to the movable valve body.

4. A standpipe apparatus for conveying distillation gases from a carbonization chamber to a collecting main, comprising: a riser pipe receiving at its lower end the gases, an upper discharge pipe extending from the top of said riser pipe, a lower discharge pipe connected laterally with the collecting main below the longitudinal axis of the latter, a drop valve body located within the lower discharge pipe and movable upwardly to shut off the riser pipe from the collecting main, and a spray nozzle mounted in the top of the upper discharge pipe above the valve body for spraying downwardly through the connected pair of discharge pipes and also on to the movable valve body.

5. A standpipe apparatus for conveying distillation gases from a carbonization chamber to a collecting main, comprising: a riser pipe receiving at its lower end the gases, a discharge pipe extending downwardly from the top of said riser pipe and connected laterally with the collecting main below the longitudinal axis of the latter, a drop valve located within the discharge pipe, and means for spraying downwardly through the discharge pipe and on to the said drop valve.

6. A standpipe apparatus for conveying distillation gases from a carbonization chamber to a collecting main, comprising: a riser pipe receiving at its lower end the gases, a discharge pipe extending substantially directly downwardly from the top of said riser pipe and connected with the collecting main, a drop valve located within the discharge pipe, and means located above the drop valve both when in its elevated and when in its lowered position for spraying downwardly through the discharge pipe and on to the said drop valve.

7. A standpipe apparatus for conveying distillation gases from a carbonization chamber to a collecting main, comprising: a riser pipe receiving at its lower end the gases, a discharge pipe extending downwardly from the top of said riser pipe and connected laterally with the collecting main, a drop valve located within the discharge pipe, and means for spraying downwardly through the discharge pipe and on to said drop valve.

8. A standpipe apparatus for conveying distillation gases from a carbonization chamber to a collecting main, comprising: a riser pipe receiving at its lower end the gases, a discharge pipe extending substantially directly downwardly from the top of said riser pipe and connected with the collecting main below the top of the riser pipe, a controlling valve within said discharge pipe, and means located above said valve both when in its open and when in its closed position for spraying downwardly through said discharge pipe.

9. A standpipe apparatus for conveying distillation gases from a carbonization chamber to a collecting main, comprising: a riser pipe receiving at its lower end the gases, a discharge pipe extending substantially directly downwardly from the top of and vertically along side of said riser pipe, and a valve permitting a continuous flow of flushing fluid through said valve and discharge pipe.

10. A standpipe apparatus for conveying distillation gases from a carbonization chamber to a collecting main, comprising: a riser pipe receiving at its lower end the gases, and a discharge pipe extending downwardly from the top of and vertically along side of said riser pipe and connected laterally with the collecting main.

11. A standpipe apparatus for conveying distillation gases from a carbonization chamber to a collecting main, comprising: a riser pipe receiving at its lower end the gases and having its top substantially erect, a downcomer discharge pipe extending substantially directly downwardly from said top of and substantially vertically along the side of said riser pipe and means for spraying the interior of said discharge pipe.

12. A standpipe apparatus for conveying distillation gases from a carbonization chamber to a collecting main, comprising: a riser pipe receiving at its lower end the gases and having its top substantially erect, a downcomer discharge pipe extending substantially directly downwardly from said top of and substantially vertically along the side of said riser pipe, a valve controlling the passageway through said discharge pipe, and means for spraying the interior of said discharge pipe and said valve.

13. The combination defined in claim 12 in which the valve is of the overflow type.

In testimony whereof I have hereunto set my hand.

JOSEPH VAN ACKEREN.
